APPARATUS FOR REMOVING AND REPLACING THE COVER OF A FURNACE OR THE LIKE

Georg Coors, Wiesbaden, Germany, assignor to Westofen G.m.b.H., Wiesbaden, Germany, a German firm

Application April 20, 1954, Serial No. 424,481

Claims priority, application Germany April 27, 1953

10 Claims. (Cl. 268—10)

The present invention relates to apparatus for removing and replacing the cover of a furnace, soaking pit or the like.

In many furnaces, soaking pits and the like, the material to be treated is charged or introduced into the pit or furnace, and is discharged or withdrawn therefrom, through the top. For this purpose, the flat or arched cover of the pit or furnace, which tightly closes the pit or furnace chamber or interior at the top thereof, is raised from its closing position and moved away from the pit or furnace opening and, after recharging of the pit or furnace, is replaced in such closing position. The usual size of such a cover, and the temperature at which it is generally found, necessitate the employment of special apparatus for these removing and replacing operations.

Lifting and transporting devices for such covers are known. Conventionally, the said devices slide on rails provided at one side near the pit or furnace opening. However, in such devices, the assemblies which raise and lower the cover and which operate the device, especially the motors and gear drives, are positioned on the cover, i. e. above the pit or furnace opening. Consequently, the driving assemblies, which comprise heat-sensitive material—for example, motors and the insulation thereon—are prejudicially exposed, when the cover is in closed position, to appreciable indirect heat radiation from the cover and, when the cover is in removed position, to intensive direct heat radiation. In addition, the devices provide a direct lift for the cover and also hold the entire weight of the cover as a suspended load, so that very large driving or operating units are required.

It is an object of the present invention to embody a relationship of parts for effecting the aforesaid functions, i. e. removing and replacing the cover of the pit or furnace, while being free of the prior art deficiencies and defects.

This object is realized by the present invention, the relationship of parts of which is characterized by a carriage, on the frame of which—positioned beyond the extent of the cover—there are positioned the elements for lifting and lowering the cover and for supporting the same, the driving means for said carriage being itself located exteriorly of the carriage frame. In this way, all the heat-sensitive elements or devices necessary for moving the cover are withdrawn from the prejudicial thermal action of the cover or furnace.

A presently-preferred exemplary embodiment of the invention is hereinafter described in detail with reference to the accompanying sheets of drawing. On the said sheets of drawing,

Fig. 1 is a top plan view, somewhat diagrammatic in character, of the cover and carriage;

Fig. 2 is a vertical, somewhat diagrammatic, section through the cover and carriage;

Fig. 3 is a side elevational view, somewhat diagrammatic, corresponding to Fig. 1;

Figs. 4 and 5 are detail partial views, somewhat diagrammatic, of the locking device for the cover; and

2

Fig. 6 is a side elevation, somewhat diagrammatic in character, of the cover and carriage with the locking device.

The pit or furnace chamber 1, only the top of which is shown on the drawings, is tightly sealed at the top by the flat cover 3 which is provided on all four sides with a continuous depending flange 3' which extends into the sand pocket 2 which, correspondingly, extends continuously around the top of the pit or furnace chamber 1 (see Fig. 2 of the drawings). The apparatus according to the present invention functions to remove the cover 3 from and to reinsert it into the sand pocket 2.

The said apparatus comprises a carriage 4, on the frame of which and beyond the extent of the cover 3, there are provided the elements for raising and lowering and transporting the said cover. The driving means 5 for said carriage is, in turn, positioned exteriorly of the carriage frame. Advantageously, the carriage 4 is provided with a U-shaped frame, the legs 6 and 7 of which extend in the direction of movement of the carriage, the elements 8 and 9 which effect the raising and lowering of the cover being positioned on the said legs 6 and 7. As shown more particularly in Figs. 1, 3 and 6, two sets of such elements are provided, one set on each leg, each set comprising spaced and aligned members 8 and 9. The latter are constructed as upstanding plates which are essentially wedge-shaped in side elevation (see Fig. 3). The upper inclined surface of each of these wedge-shaped elements or cam members 8 and 9 terminates in a horizontal extension surface or, preferably as illustrated, in extension surfaces 8' and 9' which incline slightly downwardly in a direction opposite to that of the original incline. These extension surfaces, which function as supporting surfaces, are each provided at the outer end thereof with an upstanding limiting abutment 8" or 9".

Mounted on the cover 3 and extending thereacross in spaced relationship thereto are carrier beams 10, which project at each end beyond the cover 3, and are provided on each projecting end with rollers 11 or 12. The beams 10 are so dimensioned that the said rollers comprise within their path of movement the aforesaid surfaces of elements 8 and 9. The beams are spaced apart to an extent equal to the space between members 8 and 9 (see Fig. 1).

45 The carriage 4 is driven by motor 5 which is preferably fixedly positioned exteriorly of the carriage on a suitable and conventional support, and the drive is effected through the medium of gearing 13, gear shaft 13', pulleys 14, pulleys 15 and driving ropes 16. Pulleys 14 and 15 are fixedly mounted independently of the carriage 4 and cover 3. The ropes 16 severally extend on each side, just beyond the adjacent frame legs 6 and 7. The ends of each rope 16 are fastened to lugs 16', being provided on each side of the carriage 4.

55 Lifting of the cover 3 takes place upon movement of the carriage 4 from its initial position (shown in solid lines in Fig. 1 and corresponding to the closing position of the cover). This movement (to the left in Fig. 1), effected with the aid of motor 5 and interposed elements

60 (gearing, pulleys, ropes), causes the cam or wedge-shaped members 8 and 9 of each of the two sets of such members to be positioned under the corresponding rollers 11, 12 of the carrier beams 10. Continued movement of the carriage 4 runs the said rollers onto the cam members, 65 whereby the cover 3 is raised to an extent corresponding to the vertical height of the said members, such vertical height being at least slightly greater than the depth of the sand pocket 2. In such raised position, the cover 3 is free to be moved relative to the pit or furnace. It 70 is now resting on the cam members 8 and 9, i. e. is carried by the carriage 4 as a static load. The carriage itself is movable on rails 18 on which wheels 17 of the

carriage run. One rail is provided at each side of the pit or furnace at about the level of the pit or furnace opening, see Fig. 2.

During the lifting operation, the cover 3 is secured against relative displacement in the direction of movement of the carriage 4, by means of a locking device located in the free space between the carriage and the cover; see e. g. Fig. 4. In the preferred embodiment according to the invention, this locking device takes the form of a double-armed angular lever 20, 21 which oscillates about its pivot at the vertex of the angle, the end of each arm being provided with a roller 20', 21'. The lever arms 20, 21 are of different lengths; the rollers 20', 21' may be of the same or different sizes.

When the cover 3 is in its position closing the opening of the pit or furnace, i. e. in the initial position of the cover 3 and carriage 4, the double-armed lever constituting the locking device 19 is maintained in its uppermost position by the guide member 22, which is preferably angular in configuration (see Fig. 6) and is secured to the inner side of frame leg 6. In this position, the roller 21 is positioned behind the widened end 23 of the cover 3. A similar locking device is also provided on the other side of the cover, in which case a guide member 22 is also provided on the inner side of frame leg 7 (see Fig. 4).

Upon movement of the carriage, the roller 20 of each locking device moves along the corresponding guide member 22, the length of which corresponds to the length of the cam members 8 or 9, these being of identical lengths. During this movement, the rollers 11 and 12 of the cover carrying beams 10 run onto the cam members 8 and 9. When the rollers 20 reach the end of the guide pieces 22, they are unsupported upon further movement of the carriage. Thereupon the longer arms 21, which moreover may be provided with the heavier rollers 21', gravitate downwardly and release the cover 3.

The cover 3 which is now seated on the cam members 8, i. e. is mounted on the carriage 4, can now be moved away from the pit or furnace opening by means of carriage 4 through the medium of the driving motor 5 and aforesaid interposed elements.

Return movement for replacement of the cover 3 onto the pit or furnace opening involves return movement of the carriage 4, and this is also effected from the motor 5, suitable and conventional means being provided for reversing the direction of movement transmitted to the ropes 16. Upon such return movement, the cover abuts against the bumper 24 when it (the cover) reaches its position above the opening. The carriage 4 then continues to move (to the right, in Fig. 1) to an extent equal to the length of the wedge or cam members 8 or 9, whereby the rollers 10 and 11 of the cover carrying beams 10 run off the said members. This lowers the cover 3 until the depending flanges 3' are again positioned in the same pocket 2. Simultaneously, the guide members 22 have run onto the rollers 20 of the locking devices, so that the rollers 21 assume their locking positions behind the widened end 23 of the cover.

Having thus disclosed the invention, what is claimed is:

1. Apparatus for raising and lowering and for transporting the cover of an upwardly open furnace or the like, comprising a carriage separate from said cover and movable along a path comprising the opening of said furnace,

said carriage straddling said opening and the cover thereof when in position thereover, carrier beams extending upwardly from said cover to a position above said carriage when the cover and carriage are in superposed relationship, lifting cams mounted on said carriage on each side thereof and beyond the extent of said opening when the carriage is thereover, said carrier beams being engageable by said lifting cams as the carriage moves along its said path and thereby raising said cover from said opening, said cover being entrainable along with said carriage to a point remote from said opening as said carriage continues to move along said path, and means remote from said opening for imparting movement to said carriage.

2. The relationship of parts according to claim 1, said last named means moving said carriage in both directions along said path, means for limiting the movement of said cover during the return movement of said carriage and entrained cover whereby, upon continued return movement of said carriage the carrier beams are disengaged from said cams and the cover is dissociated from said carriage and replaced on said furnace opening.

3. Apparatus as defined in claim 1, said carriage being U-shaped and comprising legs extending in the direction of movement of the carriage, said lifting cams being mounted on said legs.

4. Apparatus according to claim 3, wherein said lifting cams are wedge-shaped plates having inclined upper surfaces, whereby they effectively function as inclined planes.

5. Apparatus according to claim 4, wherein the carrier beams extend across the top of said cover, each beam projecting beyond the sides of the cover and each projecting portion having a roller mounted thereon, said rollers being positioned in alignment with the upper surfaces of said lifting cams whereby relative movement between said carriage and cover causes said rollers to run onto said surfaces and effects the lifting of said cover.

6. Apparatus according to claim 1, wherein the location of said driving means is fixed.

7. Apparatus according to claim 1, said carriage being laterally spaced from said cover, and a locking device interposed in said space for securing the cover against displacement in the direction of movement of said carriage during lifting of said cover.

8. Apparatus according to claim 7, said locking device comprising a double-armed angular lever pivoted at the vertex thereof, and means for effecting interengagement between one said arm and said cover to secure the latter during lifting thereof.

9. Apparatus according to claim 8, wherein the arms of said lever are of unequal length and a roller is journaled on the end of each arm.

10. Apparatus according to claim 9, comprising a guide member for said lever mounted on the inside of said carriage frame.
